UNITED STATES PATENT OFFICE.

JOHN H. GOEHST, OF CHICAGO, ILLINOIS.

DESIGN FOR A CEILING-FIXTURE FOR ELECTRIC LAMPS.

No. 38,972.

Specification for Design.

Patented Dec. 31, 1907.

Application filed October 5, 1907. Serial No. 396,120. Term of patent 14 years.

To all whom it may concern:

Be it known that I, JOHN H. GOEHST, a citizen of the United States, residing in Chicago, in the county of Cook and State of Illinois, have invented a new, original, and ornamental Design for Ceiling-Fixtures for Electric Lamps, of which the following is a specification, reference being had to the accompanying drawing, forming part thereof.

The figure is a perspective view of a ceiling

fixture for electric lamps showing my new design.

I claim.

The ornamental design for a ceiling fixture for electric lamps as shown.

JOHN H. GOEHST.
